CLAIM

The ornamental design for a combined ceiling fan and lights, as shown and described.

DESCRIPTION

FIG. 1 is a bottom perspective view of a combined ceiling fan and light, showing my new design;

FIG. 2 is an end elevational view thereof, the opposite end being a mirror image of that shown;

FIG. 3 is a bottom plan view thereof;

FIG. 4 is a side elevational view thereof, with the cylinder rotated upward so that the ribs are located at the vertical center of the ceiling fan, the opposite side being a mirror image of that shown; and,

FIG. 5 is a top plan view thereof.

FIG. 1

FIG. 2

FIG. 4

FIG. 3

FIG. 5
